UNITED STATES PATENT OFFICE

LEROY G. LEICHNER, OF ASHLAND, KENTUCKY, ASSIGNEE TO THE AMERICAN ROLLING MILL COMPANY, OF MIDDLETOWN, OHIO, A CORPORATION OF OHIO

INTERMEDIATE TABLE FOR DOUBLE SHEARS

Application filed September 4, 1928. Serial No. 303,682.

In double shearing, which is to say, the process of shearing both ends of a metallic or other sheet simultaneously, it is essential that there be some support between the two shear beds to hold the sheet upon a horizontal plane, since as will be readily understood, any substantial deflection will vary the length of the cut. Again in shearing iron sheets it is quite essential that there be between the 10 shears a table which will be in the nature of a conveyor or a surface over which the sheet may be moved. My invention is addressed to such intermediate tables.

Hitherto a chief problem connected with 15 intermediate tables has been adjustability. It is essential in the double shearing, for example of iron, that one shear be movable upon the bed to allow the length of the sheared sheets to vary from five feet up to about 20 twelve feet or more. The practice has been to provide, for an intermediate table, a bracket attached to each shear bed. Whenever the position of the movable shear was changed to vary the cut, these brackets had 25 to be unbolted and bolted together in the new position. This consumed a great deal of time, and was particularly disadvantageous in its application to the double cut-off shears at the end of the so-called "continuous strip" processes in the iron and steel industry. Here, for continuous pickling, annealing or the like, sheets are stitched or otherwise fastened together and in this fashion led through various instrumentalities at 30 comparatively high speeds. Double shears must be readily adjustable without an appreciable stopping of the process.

It is an object of my invention to provide 35 an intermediate table which, while adequate to support the sheets in a horizontal plane, does not interfere with the speedy adjustment of shear distances.

It is another object of my invention to provide 40 an intermediate table which automatically adjusts itself to varying shear distances, so that the setting of the shears for a different cut involves only the shifting of the movable shear along the bed, and does 45 not involve all of those labor and time con-

suming operations hitherto involved in taking apart and putting together the table.

It should be noted also that since double shears are frequently used for metallic sheets which are or are intended to be made into highly finished sheets, an intermediate table comprising rails or a flat metallic surface over which the sheets are drawn is unsuitable because of the marring of the sheet-surface. Attempts to combine rollers or other conveyor mechanism with old shear tables have complicated their adjustment as will be readily understood. It is therefore still another object of my invention to provide in an intermediate table of my new type, 55 means for conveying the stock without marring its surface. 60

These and other objects of my invention which will be apparent to one skilled in the art upon reading these specifications, I accomplish by that certain construction and arrangement of parts of which I shall now describe a preferred embodiment. This preferred embodiment has to do with the particular mechanism for which I devised, and 70 in which I am now using my invention, 75 namely, the double cut-off shears at the end of a continuous strip process; but it will be obvious to the man skilled in the art that shears as such have no limiting relation to 80 my invention, said invention being equally as applicable to other double and/or adjustable mechanism such as punches, drill presses or many others, and that it is of importance alone as an adjustable conveyor. Reference 85 is hereby made to the drawings which form a part of this specification.

In the drawings:

Figure 1 is a side elevation, partially diagrammatic, of a double shear mechanism embodying my intermediate table. 90

Figure 1^a is an enlarged view of the chain.

Figure 2^a is a plan of the same mechanism.

I have shown generally at 1 the bed of a double cut-off shear upon which is mounted a fixed shear 2 and a movable shear 3 which will be thought of as equipped with the well known mechanism whereby it may be moved toward or away from the fixed shear 2, along the bed, and fixed in place where desired. 95 100

Such mechanism forms no part of my invention.

My new intermediate table comprises two strands of steel chain indicated broadly as 4 and 5, which may be set at any desired center distance according to the width of the sheet to be run. The chain strands comprise links 5^a, pins 6 and collars 7. There are two collars upon each pin, and intermediate them 10 I mount a disc 8, preferably of fibre so as not to scratch the sheets conveyed thereover. One of these discs is mounted at each joint of each strand of the chain, and it will be clear that the two strands will together form 15 a conveyor if stretched taut and parallel. The discs, of course, are free to roll idle upon the connecting pins.

The fixed shear 2 has a fixed shear table, adjacent which I fasten brackets 10 to which 20 the chain-strand ends are attached.

The chain strands are adapted to be supported by tension intermediate the shears; but upon the movable shear 3 I provide a support therefor which is adapted to hold the 25 effective end of my table in line with the shear table top 11 of the movable shear. This support, which I have indicated broadly by the numeral 12 is in the nature of a guide over which the chain strand will slip, 30 and which serves to carry the chain strand down below the level of the table 11, by changing its direction against tension. A second guide is provided to change the direction of the chain strand and bring it back to 35 the horizontal at a new level. The general purpose of these guides is to get the unused or ineffective end of my chain strands out of the way of the movable shear shear-table 11 while permitting the tension exerted upon 40 the chain strands to be effective in holding the intermediate-table-forming portions in position. The guide 12, of course also supports the end of my intermediate table at the right height.

45 The guide-supports are conveniently made comprising arcuate supporting parts 13 and 14 which are fastened to an S shaped member 16 one end of which is attached directly to the frame of the movable shear while the 50 other may be supported by a strut 17. This strut may be made adjustable, if desired, to vary the height of the intermediate table end. The arcuate support 13 has its convex portion disposed upwardly, while 14 is convex 55 downwardly. These supports engage the chain strands, or the cables next to be described, in such a way that they may be tensioned thereagainst, but may be moved thereover when the movable shear is shifted. 60 Portions 18 may abut the sides of the member 13 so as to form a channel holding the chains against sidewise slippage, and a similar arrangement may be made to hold the chain strands or cables upon the member 14. 65 The entire guiding and supporting mecha-

nism, may, if desired, be constructed of heavy angle stock; but its construction may be varied without departing from the spirit of this invention. Its essential features are the arcuate guide-supports, or equivalent means for 70 the purpose, and means for holding the guide supports in the proper location.

Tension is exerted upon the chain strands by cables. These I prefer to make of wire 75 rope, cut to the proper length, and formed with loops at either end. One of these loops passes about a connecting pin at the end of each chain strand, while the other engages a hook-bolt or eye-bolt 19. This bolt passes through an abutment upon the bed 1. A coiled spring 21 is placed about the shank of the bolt. It presses against the abutment 80 at one end, and at the other is surmounted by a washer 22 held in place upon the bolt 19 by a nut 23. The abutment 20 is rigidly 85 mounted upon the bed, and is suitably braced. It may be conveniently constructed of heavy angle and sheet stock as shown; but it may have other constructions. It is essentially 90 a means against which the chain strands may be tensioned. Further, the tensioning means may be varied at will, and instead of cable, spring and eyebolt, may comprise such other well-known equivalents as may be desired. With the mechanism which I have described, 95 it will be evident that when the nut 23 is tightened upon the bolt, the cables 24, if of proper length, will pull upon the chain strand ends, and that the chain strands may be tensioned to any degree desired against the guide-supports 13, 14 and the brackets 10. It will be further evident that when so tensioned the chain strands form an effective intermediate table 4 for the double shears. 100

The movable shear 3 can now be moved either toward or away from the fixed shear along the bed. When this is done, the chain strands slip over the guide supports and the effective length of the intermediate table which they form, changes automatically, but without change of tension. The operator does nothing toward the adjustment of the table other than tightening the tension whenever the tension has become too loose, by taking up the nut 23 against the spring 21. 105

Various modifications of my invention will be within the purview of those skilled in the art to construct without departing from the spirit of my invention.

Having described a preferred embodiment of it, what I claim as new and desire to secure by Letters Patent is:

1. An intermediate table for coacting mechanisms which include a fixed mechanism and a mechanism movable with relation thereto, said intermediate table comprising flexible link members and tensioning means therefor whereby they may be supported in table-like formation. 125

2. An intermediate table of variable 130

length for coacting mechanisms of variable distance from each other, one of said mechanisms being relatively fixed and the other movable, said table comprising flexible link members attached at one end to the fixed mechanism and tensioned independently of the movable mechanism.

3. An intermediate table for co-acting mechanisms one of which is movable with reference to the other comprising a link construction fastened at one end to the immovable mechanism and tensioned at the other independently of the movable mechanism and a support on said movable mechanism 15 to hold said link construction at the proper height.

4. An intermediate table for co-acting mechanisms one of which is fixed and the other relatively movable comprising a link 20 construction fastened at one end to the immovable mechanism and tensioned at the other independently of the movable mechanism and a support on said movable mechanism to hold said link construction at the 25 proper height, said link construction adapted to slide over said support as said movable mechanism is moved whereby the effective length of said table may be changed.

5. An intermediate table for coacting 30 mechanisms movable relatively to each other, which comprises a link construction and tensioning means whereby said link construction is held in table-like formation, said tensioning means being independent of 35 one of said mechanisms.

6. An intermediate table for coacting mechanisms movable relatively to each other which comprises a link construction and a tensioning means therefor independent of 40 one of said mechanisms, a support for said table adapted to uphold the effective length thereof at the proper height, and adapted to lead out of the way the ineffective length thereof without destroying the tension 45 thereof.

7. An intermediate table for coacting mechanisms movable relatively to each other which comprises a link construction and a tensioning means therefor independent of 50 one of said mechanisms, a support for said table adapted to uphold the effective length thereof at the proper height, and adapted to lead out of the way the ineffective length thereof without destroying the tension thereof, said support being mounted upon one of said mechanisms whereby said mechanisms may be moved to varying distances from each other thereby affecting the effective length of said table, without 55 destroying the tension thereof and without the necessity of independent adjustment.

8. An intermediate table for coacting mechanisms movable relatively to each other which comprises chain strands attached to 60 the immovable mechanism and tensioning

means for said chain strands whereby they may be held in table-like formation, means for conducting the ineffective lengths of said chain strands out of the way without destroying the tension thereof whereby the movable mechanism may be moved, with reference to the fixed mechanism without varying the adjustment of said table.

9. In a device comprising coacting mechanisms, one fixed on a bed, the other movable on said bed, so as to vary the distance between said mechanisms, an intermediate table therefor comprising a link construction rigidly fixed at one end and tensioned at the other with respect to said bed, 75 means for holding said table at the proper height with reference to said coacting mechanisms and movable means for conducting out of the way the ineffective length of said link construction without interrupting the tension thereof, whereby said movable mechanism may be moved upon said bed and whereby the effective length of said table may be varied with said movement without 80 interrupting the adjustment thereof.

10. In a device comprising a bed, a fixed coacting mechanism and a movable coacting mechanism thereon, an intermediate table between said mechanisms comprising a link construction affixed at one end to said immovable mechanism, an abutment on said bed beyond said movable mechanism, tensioning means between said abutment at the other end of said link construction whereby said link construction may be held in table 90 like formation, means for supporting said link construction at the proper height and means for conducting out of the way the ineffective length of said link construction.

11. In a device comprising a bed, a fixed coacting mechanism and a movable coacting mechanism thereon, an intermediate table between said mechanisms comprising a link construction affixed at one end to said immovable mechanism, an abutment on said bed beyond said movable mechanism, tensioning means between said abutment at the other end of said link construction whereby said link construction may be held in table like formation, means for supporting said link construction at the proper height and means for conducting out of the way the ineffective length of said link construction, said means affixed to said movable mechanism, said link construction adapted to ride over said means whereby when said movable mechanism is moved, the effective length of said table will be varied without disturbing the adjustment thereof.

12. In a device comprising a bed, a fixed coacting mechanism thereon and a movable coacting mechanism thereon, an intermediate table for said mechanisms comprising two strands of chain, brackets upon said fixed mechanism adapted to hold one end of 130

said chain at table height, means on said movable mechanism adapted to hold said chains at table height and to conduct out of the way the ineffective length of said chains, an abutment on said bed beyond said movable member and tensioning means for tensioning the other end of said chains against said abutment, said chains adapted to ride over said supporting and conducting means during movement of said movable member.

13. In a device comprising a bed, a fixed coacting mechanism thereon, a movable coacting mechanism thereon and an intermediate table variable without adjustment as the distance between said mechanisms is varied, said table comprising chain strands attached at one end to brackets fixed at table height upon said immovable mechanism, an arcuate support on said movable mechanism adapted to hold said chain strands intermediate their ends at table height on said movable mechanism and adapted to permit a change in direction of said chain strands, a second obverse arcuate support upon said movable mechanism adapted to bring the direction of said chain strands back to the original but upon a different plane, an abutment upon said bed, tensioning means affixed to said abutment and to the other end of said chain strands adapted to tension said chain strands and to hold that portion of them lying between said brackets and said supports in table-like formation, said chain strands adapted to slide over said arcuate supports when said movable mechanism is moved, whereby by the movement of said movable mechanism the effective length of said table may be varied automatically.

14. In a device comprising a bed, a fixed coacting mechanism thereon, a movable coacting mechanism thereon and an intermediate table variable without adjustment, as the distance between said mechanisms is varied, said table comprising chain strands attached at one end to brackets fixed at table height upon said immovable mechanism, an arcuate support on said movable mechanism adapted to hold said chain strands intermediate their ends at table height on said movable mechanism and adapted to permit a change in direction of said chain strands, a second obverse arcuate support upon said movable mechanism adapted to bring the direction of said chain strands back to the original but upon a different plane, an abutment upon said bed, tensioning means affixed to said abutment and to the other end of said chain strands adapted to tension said chain strands and to hold that portion of them lying between said brackets and said supports in table-like formation, said chain strands adapted to slide over said arcuate supports when said movable mechanism is moved, whereby the movement of said movable mechanism the effective length of said table

may be varied automatically, said tensioning means comprising bolts and springs.

15. In a device comprising a bed, a fixed coacting mechanism thereon, a movable coacting mechanism thereon and an intermediate table variable without adjustment, as the distance between said mechanisms is varied, said table comprising chain strands attached at one end to brackets fixed at table height upon said immovable mechanism, an arcuate support on said movable mechanism adapted to hold said chain strands intermediate their ends at table height on said movable mechanism and adapted to permit a change in direction of said chain strands, a second obverse arcuate support upon said movable mechanism adapted to bring the direction of said chain strands back to the original but upon a different plane, an abutment upon said bed, tensioning means affixed to said abutment and to the other end of said chain strands adapted to tension said chain strands and to hold that portion of them lying between said brackets and said supports in table like formation, said chain strands adapted to slide over said arcuate supports when said movable mechanism is moved whereby by the movement of said movable mechanism the effective length of said table may be varied automatically, said chain strands comprising links and connecting pins and fiber discs forming a non-marring conveyor thereof.

16. In a double shear, a bed, a fixed shear having a table thereon, a movable shear thereon, brackets affixed to the shear table of the immovable shear, chain strands affixed at one end to said brackets, an arcuate support affixed to said movable shear and adapted to support said chain strands at table height adjacent the shear table of said movable shear and adapted to conduct said chain strands downwardly, a second obverse arcuate bracket upon said movable shear adapted again to change the direction of said chain strands whereby said chain strands are conducted beneath the shear table of said movable shear, an abutment on said bed beyond said movable shear, and tensioning means on said chain strand ends against said abutment, said chain strands adapted to slide over said arcuate supports during movement of said movable shear, said abutment and tensioning means being independent of said movable shear whereby when said movable shear is moved, the effective length of the intermediate table is varied without disturbing the tension thereof and without the necessity of separate adjustment.

17. In a double shear, a bed, a fixed shear having a table thereon, a movable shear thereon, brackets affixed to the shear table of the immovable shear, chain strands affixed at one end to said brackets, an arcuate support affixed to said movable shear and

adapted to support said chain strands at table height adjacent the shear table of said movable shear and adapted to conduct said chain strands downwardly, a second obverse 5 arcuate support upon said movable shear adapted again to change the direction of said chain strands whereby said chain strands are conducted beneath the shear table of said movable shear, an abutment on said bed beyond 10 said movable shear, and tensioning means on said chain strand ends against said abutment, said chain strands adapted to slide over said arcuate supports during movement of said movable shear, said abutment and 15 tensioning means being independent of said movable shear whereby when said movable shear is moved, the effective length of the intermediate table is varied without disturbing the tension thereof and without the necessity 20 of separate adjustment, said chains comprising links and pins and fiber discs freely journalled on said pins whereby a non-marring conveyor is formed of said intermediate table.
